werke G. m. b. H., Frankfort-on-the-Main, Ger-
many, a corporation of Germany

Application March 28, 1936, Serial No. 71,418
In Germany April 18, 1935

12 Claims. (Cl. 178—23)

This invention relates to printing telegraph apparatus and, more specifically, to answer back devices with which such apparatus can be provided. These answer back devices are provided particularly in teleprinting installations operated through exchanges, to enable an identification signal to be sent automatically from the called station to the calling station indicating, for example, the name of the called station. The name transmitter is generally brought automatically into operation at the beginning of the communication and sends out its signal one or more times.

In accordance with the invention, the answer back device is arranged not only so that it can be brought automatically into operation on connection to the called station but also so that it can be brought into operation at will through the operation of key controlled contacts. The identification signal can then also be sent out by the calling subscriber, for example, at the conclusion of the communication.

The answer back device of the calling station may be arranged so that it can be brought into operation by a single depression of a key and so that the signature of the sender can be transmitted at the end of the transmitted text. This represents a substantial simplification in operation of the apparatus and enables good use to be made of the answer back device.

An example of a telegraph printing apparatus provided in accordance with the invention with an answer back device is illustrated in the accompanying drawing. This shows the circuit diagram for an apparatus in a telegraph station S₁ constructed to operate both as a transmitter and as a receiver and for uninterrupted double current operation. The connections at the station S₂ at the other end of the line L are formed in the same way.

The various relay contacts are, in accordance with the usual convention, designated in the drawing by small letters corresponding to the capital letters used to designate the relays on which they depend. In addition to the relay contacts, there are also the following contacts:—

ET—controlled by a particular transmitting key.

Unt₁ and Unt₂—controlled by another transmitting key.

zz—closed by the "shift" key for sending a "shift" signal and which remains closed until the "shift back" signal is sent out.

wd—controlled by the transmitting key which

brings about transmission of the "who-are-you" signal.

ZMS—controlled by a cam of the transmitter shaft of the printer.

skr and ska—the transmitting contacts which are actuated in phase with the signal sequence to be transmitted.

ZME—controlled by a cam of the receiver shaft of the printer.

WD—controlled by the receiver on reception of the "who-are-you" signal.

Kl—controlled by the receiver on reception of a special signal.

pap—controlled by the paper of the printer.

nskr and nska—the "answer back" transmitting contacts.

nhr and nha—controlled by the "answer back" device as long as it is driven by the motor.

nt—controlled by the "answer back" device at the instant at which it is declutched from the motor.

The apparatus is driven by a motor M. This motor drives, in the transmitter, the transmitting distributor shaft (contacts skr and ska) and in the receiver, the not illustrated distributor for translation of the incoming signal impulses and the not illustrated printer.

Each station also has a time switch mechanism driven by the motor M associated with it which serves, among other things, for interrupting the motor circuit should a given length of time elapse during which no signals are sent or received. This time switch device is brought into the operative position by energization of a magnet ZS and the time is counted from the instant at which the magnet ZS is de-energized.

The station is also provided with an answer back device of suitable construction which is made operative by an energization of short duration of a magnet N. The answer back device may comprise a drum having cams distributed over its circumference in a manner corresponding to the signal characterizing the station to which it belongs. These cams control the contacts nska and nska. The drum is clutched to the motor M by the magnet N upon a short energization of this magnet for a number of revolutions during which time the contacts nhr and nha are thrown. The drum is declutched automatically at the end of these revolutions. A contact nt is opened for a short time by the drum shortly before the answer back device is declutched.

The contacts skr and nska of the transmitter and the answer back device open in phase with the signal transmission. The contacts ska and

55

nska on the other hand close a short time before the opening and also open a short time after the closing of the contacts *skr* and *nskr*.

The receiver is controlled by a polarized line relay *ER* lying in the line *L* and influencing the receiving magnet *EM*.

The operation over the line *L* takes place with double current. In each station there is a marking battery *e* and a spacing battery *E*. The positive pole of the marking battery of the illustrated station is connected to earth which forms the return line; in the unillustrated station at the other end of the line the negative pole of the marking battery is connected to earth in the same way. Similarly, the spacing batteries of the two stations are connected oppositely.

The earth connection for the spacing batteries *E* runs on the marking side of the contact *pap*. This contact is controlled by the paper feed mechanism (not illustrated) in such a way that it is reversed on interruption of the paper feed for example, in consequence of the failure of supply.

A test key *PT* having contacts 1—3 is provided for determining whether the telegraph apparatus and its answer back device are in good working order. This can be determined, for example, by causing the transmitted text to be recorded only in the receiver of the transmitting station. The remaining connections of the telegraph apparatus serve for ensuring undisturbed operation. The apparatus operates in the following manner:

The marking circuit runs as follows: earth, battery *e* of the illustrated station, contact 1, answer back contact *nskr*, transmitting contact *skr*, contact 5, line relay *ER*, line *L*, and thence to the identically connected but not illustrated station at the other end of the line and the marking battery *e* connected therein in series and back to earth.

This marking current energizes the polarized relay *ER* in such a way that the contact *er* assumes the illustrated position.

When it is desired to transmit a communication from a calling to the called station, the switching in key *ET* on the keyboard of the transmitter of the calling station is actuated so that a circuit is closed for the magnet *ZS* of the time switch mechanism as long as the key is depressed and a special code signal is set up and transmitted through the agency of the transmitter combination elements.

The energization of the magnet *ZS*, in a manner which needs no detailed description, causes the contacts *zs1*, *zs2* and *zs3* to be operated. The contact *zs3* closes the circuit for the driving motor *M* and the transmitting apparatus is thus made ready for operation. The contact *zs1* prepares the connection of the spacing current battery *E*. The contact *zs2* causes the negative current to flow through the contact 7 to the magnet *EM* which, therefore, responds but without as yet causing anything else to happen.

During running of the motor *M*, the code signal which has been set up by depression of the switching-in key *ET* is transmitted through the line *L*. This signal is preferably a five-unit signal consisting of a start impulse, five successive spacing current impulses and a stop, marking current impulse. The contact *skr* remains open during the transmission both of the start impulse and of the five spacing impulses and is only closed on transmission of the stop impulse. Throughout the time during which the contact *skr* re-

mains open, the contact *skr* remains closed and connects the spacing current battery *E* to the line *L* through the contact 3 of the key *PT* and the contacts *zs1*, *sp3* and *skr* and *nskr*. This causes reversal of the contact *er* of the line relay *ER* in both stations. As the signal arrives for transmission at a time when the motor *M* at the transmitting end is just starting, the time during which the contact *skr* is maintained open, or the time during which the battery *E* is connected, is much longer than it would be were the signals to arrive for transmission when the motor is running at its normal speed. The contact *er* is therefore reversed for this correspondingly longer time, both in the calling and in the called station.

In the called station, only the following circuit will be formed:

+, contact *er*, relay *EH*, contact *zs2*, —
The relay *EH* responds and closes a holding circuit over a resistance by means of its contact *eh1*. The contact *eh4* is closed in order that the holding circuit may be independent of the contact *zs2* but dependent upon the contact *th* of a thermo-relay *TH* which is switched in by the contact *eh3* to interrupt the holding circuit after a given time. By means of the contact *eh5*, an acoustic signal is given by the bell *KL* or an optical signal by the lamp *UL* which indicates that a communication is starting. If a special code signal is sent out which reverses the contact *kl* in the receiver of the called station, the indication signal can be switched in at will. This signal is also switched in by means of the paper contact *pap* and acts as an alarm signal should the paper feed fail.

The magnet *ZS* in the called station is connected to the source of current *AS* by means of the contact *eh2* so that the time switch mechanism also comes into operation in the called station and closes the contacts *zs1*—*zs3* and reverses the contact *zs2*. The motor *M* in the called station is switched in by the contact *zs3* and the receiving magnet *EM* is connected to the negative terminal in a preparatory manner by the contact *zs2* so that it responds on release of the line relay *ER*. The contact *zs2* energizes a relay *SP* of the called station in the following circuit:

—, contact *zs2*, contact *eh6*, relay *SP*, +
The relay *SP*, as a precautionary measure, closes a holding circuit by means of its contact *sp5*. The contact *sp1* short circuits the transmitting contact *skr* in the called station and, by opening the contact *sp3*, prevents the switching in of the spacing current battery *E* in the called station through the contact *skr*.

Finally, the contact *sp4* in the called station prevents the magnet *N* which serves to bring its answer back device into operation from being energized by operation of the key contact *Unit*. Thus, on energization of the relay *SP* in the called station, no code signals can be transmitted from the apparatus to that station by operation of a key.

The answer back device of the called station can only be made operative by means of the contact *WD* which is controlled by the receiving apparatus. When, after a corresponding signal has been transmitted from the called station, the contact *WD* in the called station is closed in a known but not illustrated manner, the magnet *N* of the answer back device is energized and

brings into operation its mechanism for sending back an identification signal one or more times.

For transmission of the code signal bringing the answer back device of the called station into operation, a character shift key, in fact, the figures-signs key must first of all be depressed in the transmitter of the calling station. The depression of this key causes the contact *zz* to be closed until actuation of the letter key. The depression of the transmitter key which causes the transmission of the who-are-you code signal bringing the answer back device of the called station into operation, causes a temporary closing of the contact *wd*. The following circuit is then closed in the calling station:

—, contacts *zz*, *wd*, *sp2*, relay WDV, +

A holding circuit for the relay WDV is closed by the contact *wdv2* over a resistance and the contact *nt*. The answer back contacts *nskr* and *nska* of the calling station are prevented from being effective by the contacts *wdv6* and *wdv4*. This is necessary because the who-are-you code signal bringing the answer back device of the called station into operation also influences the receiver of the calling station so that the answer back device of this station is also made operative by the contact *WD* of its receiver.

Now, the answer back devices of both stations are clutched to their motors. No signals are transmitted in the calling station because the contacts *nskr* and *nska* are made inoperative by the contacts *wdv4* and *wdv6* of the energized relay WDV. The contacts *nha* and *nhr* remain actuated throughout the operation of the answer back device of the calling station so that the transmitting contacts *skr* and *ska* are made inoperative. The transmission of a signal is thus prevented if an attempt is made to transmit one by depression of a key of the keyboard while the answer back device of the calling station is in operation.

In the called station, in which the relay WDV is not operative, the answer back device sends out the series of signals associated with the designation of the station or the like, a corresponding recording being effected by means of the line relays *ER* of the called and calling stations. The transmitted text is printed in both the calling and the called stations by means of the magnets *EM*. Disturbances due to the rhythmic throwing of the contact *er* during reception of signals or when signals are simultaneously transmitted and recorded are prevented by the spark quenching device *Fu*.

The answer back devices of both stations operate simultaneously. The identification signal sent by the answer back device of the called station is completely recorded by the time the answer back device of the calling station comes to rest. Now the contacts *nha* and *nhr* of the calling station are thrown again and the contact *nt* is opened for a short time so as to open the holding circuit for the relay WDV which thus becomes de-energized. It is then possible for the transmission of the text to begin in the calling station.

After the transmission of the communication, the calling station, the relay WDV of which has again dropped, can bring its answer back device into operation by actuation of the key contacts *Unt1* and *Unt2* so that a series of code signals serving as a "signature" is transmitted. The relay *N* of the answer back device of the calling station is caused to respond by means of the key

contact *Unt1* through the contact *sp4* and, by means of the contact key *Unt2*, energizes the magnet *ZS* as a precautionary measure in order that the motor may be maintained in operation while the answer back device is running down.

The called station cannot effect such a selective bringing into operation because its relay *SP* remains held up as long as the contact *zs2* of the time switch is thrown and makes the key contact *Unt1* inoperative.

During the transmission and the reception of each signal, the transmitting or receiving distributor shaft is rotated in accordance with the known start-stop principle. During each rotation, a contact *ZMS* or *ZME* is closed by a notch 15 in the shaft which energizes the magnet *ZS* of the time switch mechanism and switches this mechanism back again into the starting position. After transmission of the communication, the time switch mechanism, unless again called upon 20 for use, is reset into its normal position after a predetermined time and its contacts *zs1*—*zs3* are thrown. The motor circuit is broken at the contact *zs3* so as to preclude operation of the time switch through the contacts *ZMS*, *ZME* and *Unt1* 25 which might be accidentally actuated and indirectly close the motor circuit again.

Uninterrupted double current operation is only used for two-way traffic. For testing the apparatus to see that it is in good working order, the switch *PT* is reversed and single current operation initiated, the contact *3* being opened so as to disconnect the spacing current battery *E*. The marking battery *e* is also disconnected at the contact *1* from the transmitting contacts *nskr* 35 and *skr* but remains connected to the line *L* as a source of marking current through the make-before-break contact *4, 5* of the switch *PT*.

During testing, the magnet *EM* is connected directly in the following local circuit:

+, contact *er*, magnet *EM*, contacts *2*, *nskr*, *skr*, 40
6, *zs2*, —

The testing can extend both to the transmitting contact *skr* and to the answer back contact *nskr*. 45 The contact *nskr* can be actuated for transmission of the name automatically by closing of the key contact *Unt1*. Now, the energization of the relay WDV effected on depression of the key *wd* is ineffective because the contact *wdv6* has been 50 made ineffective by the contact *1*.

During the testing operation, the apparatus is not entirely disconnected from the line. At the contact *8* of the testing switch *PT*, the relay *EH* is connected to the spacing side of the operative 55 contact *zs2* so that it can respond to transmitted signals, for example, to a switching-in signal and can close a holding circuit and can actuate the call signal by means of the contact *eh5*. The relay *SP* is also energized and remains energized 60 when the testing switch *PT* is re-set.

A special source of current having one pole connected to earth can be used as the local source of current for operation of the auxiliary switch means. However, if desired, the source of marking current *e* or a part of the source of spacing current *E* can be used for this purpose.

The provision of resistances in the holding circuits of the relays *EH*, *WDV* and *SP* serve the purpose of reducing current consumption as far 70 as possible. The regulating resistance connected to the magnet *EM* serves for adjusting the energizing current to be supplied to this magnet. The regulating resistance connected to the battery *E* serves for regulating the current to be 75

supplied to the line. This current has to vary in accordance with the conditions in the line and, with telegraph operation over open lines, must be capable of being finely adjusted over a wide range.

According to the particular operating conditions, various of the described safety devices can be omitted or can be replaced by other known means.

10. We claim:

1. A telegraph system comprising a line and a station at each end of said line, each station comprising a printing telegraph apparatus, an answer back device, switch means for making said answer back device operative and means adapted, on actuation by a signal received through said line and also on actuation of a key of the telegraph apparatus at the station at which said means are located, to bring said switch means into operation.

20. 2. A telegraph system according to claim 1, in which each station also comprises switch means for preventing an arbitrary bringing into operation of the answer back device under the influence of a key of the telegraph apparatus of the same station.

30. 3. A telegraph system comprising a line, a calling station at one end of the line and a called station at the other end of the line and a printing telegraph apparatus at each of said stations, each of said printing telegraph apparatus being provided with an answer back device, with switch means for bringing said answer back device into operation, with means responsive to a signal received through said line for operating said switch means, with means actuated by a key of the telegraph apparatus at the station at which said last mentioned means are located for operating said switch means, with means for transmitting a special code signal for bringing into operation the answer back device of the other station and with switch means responsive to the transmission of said code signal for cutting out said answer back device of the calling station on transmission of said special code signal from the calling station, to the called station.

40. 4. A telegraph system according to claim 1, in which each of said stations comprises a switch for connecting the printing telegraph apparatus and the answer back device at that station in a local circuit.

50. 5. A telegraph system comprising a line and a calling station and a called station at the ends of said line, each station comprising a printing telegraph apparatus adapted to transmit code signals through said line and to translate code signals received through said line for selection and printing of a type, an answer back device, switch means responsive to a code signal received through said line and translated by said printing telegraph apparatus for bringing said answer back device into operation, switch means operable by a key of the printing telegraph apparatus at the station at which said last mentioned switch means are located for bringing said answer back device into operation, switch means for rendering the answer back device of the calling station inoperative on actuation of a key of the printing telegraph apparatus of said calling station for transmitting through said line a special code signal which causes the answer back device of the called station to be made operative, said switch means being responsive to the transmission of said special code signal, and a switch for connecting said printing telegraph apparatus and said answer back device in a local

circuit, said switch being adapted on its actuation to prevent the answer back device being made inoperative under the influence of said last mentioned switch means.

6. A double current telegraph system comprising a line, a calling station at one end of said line and a called station at the other end of said line, each station comprising a printing telegraph apparatus provided with transmitting keys and adapted to transmit code signals to said line and to evaluate code signals received through said line for the selection and printing of a type, a source of marking current, a source of spacing current, a line relay, an answer back device, switch means responsive to a signal received by said line for bringing said answer back device into operation, switch means responsive to the operation of a special key of the printing telegraph apparatus at the station at which said last mentioned switch means are located for bringing said answer back device into operation, and a switch for connecting said printing telegraph apparatus and said answer back device in a local circuit, said switch being adapted on its actuation to maintain the connection of said source of marking current and of said line relay to said line.

7. A telegraph system according to claim 6, in which each station also comprises auxiliary switch means adapted to be controlled by said line relay and adapted on its actuation to switch in a call signal.

8. A telegraph system according to claim 6, in which each station comprises auxiliary switch means adapted to be controlled by said line relay and adapted to influence said switch means for making said answer back device operative, said switch means being operative also during the actuation of said switch for switching in said printing telegraph apparatus and said answer back device in a local circuit.

9. A telegraph system comprising a line, a calling station at one end of said line and a called station at the other end of said line, each station having a printing telegraph apparatus provided with transmitting keys and adapted to transmit code signals through said line on actuation of said keys and to translate code signals received through said line for the selection and printing of a type, each station being also provided with an answer back device, with switch means responsive to a signal received through said line for bringing into operation said answer back device, with switch means responsive to the actuation of a key of the printing telegraph apparatus at the station at which said last mentioned switch means are located for bringing said answer back device into operation, with an auxiliary relay adapted on its energization to close a holding circuit for itself and with switch means, controlled by said auxiliary relay on reception of code signals sent through said line, for preventing an arbitrary bringing into operation of said answer back device on actuation of a key.

10. A telegraph system comprising a line and a station at each end of said line, each of said stations having a printing telegraph apparatus provided with keys and adapted to transmit code signals through said line on actuation of said keys and to translate code signals received through said line for selection and printing of a type, each of said stations being also provided with an answer back device, with switch means responsive to a signal received through said line

for releasing said answer back device, with switch means responsive to the actuation of a special key of the printing telegraph apparatus at the station at which said last mentioned switch means are located for releasing said answer back device, and with switch means for preventing the actuation of the transmitter of said printing telegraph apparatus and of said answer back device, means also being provided for controlling said switch means in dependence upon the feed of the paper strip in said printing telegraph apparatus.

11. A telegraph system according to claim 10, comprising also auxiliary relays, call signals controlled by said auxiliary relays and in which said switch means for preventing the actuation of the transmitter of said printing telegraph apparatus and of said answer back device are adapted to control said signals.

12. A telegraph system comprising a line and a station at each end of said line, each station having a printing telegraph apparatus provided with transmitting keys and adapted to transmit code signals through said line on actuation of said keys and to translate code signals received through said line for selection and printing of a type, each station being also provided with a

line relay controlling said printing telegraph apparatus, with an answer back device, with a motor driving said printing telegraph apparatus and said answer back device, with means for clutching said answer back device to said motor, with automatically operating means for de-clutching said answer back device, with switching means responsive to a special code signal received by said line relay for operating said clutching means, with switching means responsive to an actuation of a special key of the printing telegraph apparatus at the station at which said last mentioned switch means are located for operating said clutching means, with transmitting contacts controlled by said answer back device, with switching means responsive to an actuation of said special key for making said transmitting contacts controlled by said answer back device inoperative, and with means, controlled by said answer back device when said answer back device is clutched to said motor, for preventing a transmission of code signals by said printing telegraph apparatus on actuation of its keys.
